United States Patent Office

Des. 212,602
Patented Nov. 5, 1968

212,602

SECTIONAL SOFA

Robert A. Gera, 220 Hazel Ave.,
Glencoe, Ill. 60022

Filed Mar. 14, 1968, Ser. No. 10,973

Term of patent 14 years

(Cl. D15—11)

The figure is a perspective view showing the front and ends of the sectional sofa showing my new design, the back of the sectional sofa being conventional in appearance.

I claim:

The ornamental design for a sectional sofa, as shown and described.
